UNITED STATES PATENT OFFICE

LUCILLE S. PATTERSON, OF CHICAGO, ILLINOIS

DESIGN FOR A CUSHION

Application filed March 6, 1929. Serial No. 30,366. Term of patent 7 years.

To all whom it may concern:

Be it known that I, LUCILLE S. PATTERSON, a citizen of the United States, residing at Chicago, in the county of Cook and State of Illinois, have invented a new, original, and ornamental Design for a Cushion, of which the following is a specification, reference being had to the accompanying drawings, forming a part hereof.

In the drawings:

Fig. 1 is a front view of a cushion embodying my new design, shaded to indicate contrasting colors.

Fig. 2 is a top edge view thereof.

I claim:

The ornamental design for a cushion as shown and described.

LUCILLE S. PATTERSON.
